UNITED STATES PATENT OFFICE.

HARRY W. SPANGLER, OF ALLENTOWN, PENNSYLVANIA.

BOTTLE-CLOSURE.

1,239,836.

Specification of Letters Patent. Patented Sept. 11, 1917.

Application filed April 12, 1917. Serial No. 161,459.

To all whom it may concern:

Be it known that I, HARRY W. SPANGLER, a citizen of the United States, residing at Allentown, in the county of Lehigh, State of Pennsylvania, have invented a new and useful Bottle-Closure; and I do hereby declare the following to be a full, clear, and exact description of the invention, such as will enable others skilled in the art to which it appertains to make and use the same.

This invention relates to bottles, jars and like receptacles, and particularly to an improved closure therefor, and an object of the invention is to provide a closure consisting of two pivoted disks similarly constructed, each to partially rotate relative to the other, and each having a semi-circular flange curved in cross section, so that when one disk is rotated, its flange will be brought diametrically opposite the flange of the other disk, thereby holding or locking the closure on the bead of the open end of the bottle.

A further object of the invention is to provide means on one end of each flange, whereby the disks may be partially rotated for removing and applying the cover or closure to the bottle.

In practical fields, the details of construction may necessitate alterations falling within the scope of what is claimed.

The invention comprises further features and combination of parts, as hereinafter set forth, shown in the drawings and claimed.

35 In the drawings:

Figure 1 is a view in perspective of the upper part of the bottle, showing the cover or closure applied.

Fig. 2 is a perspective view of the upper end of the bottle, showing the cover or closure in a position to be applied.

Fig. 3 is a sectional view on line 3—3 of Fig. 1.

Fig. 4 is a plan view of the cover or closure, showing parts broken away and parts in section, to more clearly disclose the structure.

Referring more especially to the drawings, 1 designates the neck of the usual form of milk bottle, the upper outer portion of the open end of which is provided with an annular bead 2, and 3 designates the closure or cover for the bottle. This cover or closure consists of a pair of disks 4 and 5, which are pivoted together axially so as to

rotate partially relatively to each other, by means of the rivet 6. Each of the complementary disks may be partially rotated, and both of said disks are provided with semi-circular flanges 7 and 8, and cut away portions 9 and 10. The flange 7 of the disk 4 is opposite the cutaway portion 9, while the flange 8 of the disk 5 is opposite the cutaway portion 10, so that when the two disks are arranged as shown in Figs. 1, 3 and 4, 60 the flanges 7 and 8 will be opposite each other. The flanges 7 and 8 are curved in cross section, so as to fit and engage the bead 2, that is, when the two disks are disposed, as shown in Figs. 1 and 3, whereby 65 the cover or closure may be held on the open end of the bottle, as shown. The disk 4, on its edge, adjacent the cut away portion 9, is provided with a slight flange 11, as shown on Figs. 2 and 3, clearly. This flange 70 is curved in cross section, and is designed to engage, and overlie the edged portion of a fiber packing 12, as shown at 13, so as to hug the packing close to the upper edge of the open end of the bottle. The flange 8, 80 when the two disks of the cover are arranged, as shown in Fig. 3, overlies the flange 11, and owing to the flange 8 engaging under the bead, the flange 11 is held tight against the edge portion of the packing. 85 The flange 7 of the disk 4 also overlies the edge portion of the fiber packing, at various points diametrically opposite the flanges 8 and 11, thereby additionally holding the packing secure. Referring to the 90 drawings, it will be seen that the flanges 7 and 8 are provided with laterally extending ears 14, one at one end of each of said flanges 7 and 8. In applying the cover or closure to a milk bottle, the two disks are so 95 rotated partly as to position the semi-circular cut away parts 9 and 10 in registration, as shown in Fig. 2 clearly, in which case the lugs 14 are adjacent each other. The cover or closure will then slide laterally into engagement with the mouth end of the bottle, and the flange 7 will engage under the bead. After so disposing the cover or closure to the milk bottle, the two ears 14 are then separated, and the disks are consequently rotated partially, until the ears 14 will assume positions diametrically opposite each other, and the flanges 7 and 8 correspondingly diametrically opposite each other, in which case, the cover or closure will be 110

locked securely on the bead of the mouth end of the bottle. A reverse partial movement of disks will permit the removal of the cover.

5 The invention having been set forth, what is claimed as new and useful, is:—

1. A closure for a milk bottle, comprising a pair of complemental disks pivoted together axially, said disks having semi-circular flanges curved in cross section to engage under the bead of the mouth end of the bottle, and provided with semi-circular cut away portions, the flange of each disk being diametrically opposite the cutaway portion of said disk, so that by partially rotating the disks, may assume positions in registration with each other, whereby the cover may be applied or removed on or from the bottle.
- 10 2. A closure for a milk bottle, comprising a pair of complemental disks pivoted together axially, said disks having semi-circular flanges curved in cross section to engage under the bead of the mouth end of the bottle, and provided with semi-circular cut away portions, the flange of each disk being diametrically opposite the cutaway portion of said disk, so that by partially rotating the disks, may assume positions in registration with each other, whereby the cover may be applied or removed on or off the bottle, one end of each flange having a lateral ear, whereby its respective disk may be rotated,

said ears adapted to coöperate to limit the disks with the cut away portions in registration, the ear of one flange to coöperate with one end of the other flange to limit the disks in their closed positions.

3. A closure for milk bottles, comprising a pair of complemental disks having semi-circular flanges curved in cross section and provided with semi-circular cut away portions, the flange of each disk being diametrically opposite the cutaway portion of said disk, and means for pivotally uniting the disks axially, whereby the disks may be rotated to register said cut away portion.

4. A closure for milk bottles, comprising a pair of complemental disks having semi-circular flanges curved in cross section and provided with semi-circular cut away portions, the flange of each disk being diametrically opposite the cutaway portion of said disk, and means for partially uniting the disks axially, whereby the disks may be rotated to register said cut away portions, and means carried by the flanges for limiting the disks in their closed and open positions.

In testimony whereof I have signed my name to this specification in the presence of two subscribing witnesses.

HARRY W. SPANGLER.
